INVENTOR.
GEORGE W. DOVER
BY *Orley H. Plant*
ATTORNEY.

UNITED STATES PATENT OFFICE.

GEORGE W. DOVER, OF CRANSTON, RHODE ISLAND.

SPINDLE STRUCTURE.

Application filed January 27, 1922. Serial No. 532,380.

To all whom it may concern:

Be it known that I, GEORGE W. DOVER, a citizen of the United States, residing at Cranston, in the county of Providence and State of Rhode Island, have invented certain new and useful Improvements in Spindle Structures, of which the following is a specification.

This invention relates to an improved spindle structure for supporting bobbins or like yarn holding devices in proper position for the unwinding of yarn therefrom during the process of weaving fabrics.

One object of the invention is to provide an improved device of this character for rotatably supporting a bobbin upon the spindle in such a manner as to prevent tilting of the bobbin during its rotation about the spindle even when the internal bores of the bobbins used vary considerably either by reason of excessive wear or as a result of being formed originally with bores of different size.

Another object of the invention is to provide means for retaining oil between the bearing supporting the bobbin and the support therefor to render the bobbin readily rotatable while preventing the yarn or threads carried by the bobbin from contact with the oil, as well as to guard the yarn or threads from becoming entangled in the moving parts.

Other objects and advantages of the invention relate to various details of construction and arrangement of the parts as will be more fully set forth in the detailed description to follow.

Referring to the drawings:

Fig. 1 is a side view of the spindle structure with a bobbin positioned thereon, the bobbin and certain portions of the spindle structure being shown in section to better illustrate certain details of construction and the relative arrangement of the parts.

Fig. 2 is a top plan view of the bearing member which normally supports the bobbin.

Fig. 3 is a detail sectional view along the line 3—3 of Fig. 2.

Fig. 4 is a detail sectional view along the line 4—4 of Fig. 2 with the spindle omitted.

Fig. 5 is a plan view of the blank from which the bearing member is formed.

Fig. 6 is a sectional view along the line 6—6 of Fig. 5.

Fig. 7 is a sectional view along the line 7—7 of Fig. 5, and,

Fig. 8 is a sectional view taken along the line 8—8 of Fig. 5.

In the embodiment of the invention illustrated herewith, 1 designates the bobbin rail by which the bobbins are carried, and 2 a base plate mounted upon the rail for supporting the spindle and bobbin. The main spindle member 3 is provided at one end with a reduced threaded portion 4 adapted to be threaded into a suitable opening in the rail whereby the spindle is held in proper operative position.

A cup-shaped supporting member 5, provided with an upstanding annular flange 6, is firmly secured to the spindle member 3 adjacent to the reduced portion 4, preferably by driving the spindle member into a central opening 7 formed in the supporting member, the opening being of suitable size to cause the spindle member to fit snugly against the adjacent parts of the supporting member when forced into the opening. A tapered bearing member 8 preferably in the form of a triangular pyramid is rotatably mounted upon the main spindle member to bear against the upper face of the supporting member and serve as a rotatable bearing for the bobbin 9. The bobbin is provided with a central bore 10 for the reception of the main spindle member.

The spindle member is provided at the end opposite from the reduced portion 4 with an axial recess 11 for receiving the reduced portion 12 of a stub shaft 13, the reduced portion 12 of the stub shaft being preferably so formed as to fit closely in the recess when driven therein whereby the stub-shaft is held against separation from the spindle. The stub-shaft 13 is provided with two annular tracks 14 for rotatably supporting a bearing sleeve 15 and reducing the friction between the sleeve and shaft, one face of said sleeve bearing against the end of the spindle member while the opposite face of the sleeve is spaced slightly from a shoulder 16 formed on the stub-shaft for retaining the sleeve against excessive axial movement relative to the spindle and affording sufficient clearance to enable the sleeve to rotate freely relative to the spindle. The bearing sleeve 15 is provided with a knurled outer surface 16' for contact with the interior bore of the bobbin to assist in impart-

ing the rotative movement of the bobbin to the sleeve whereby the bobbin supported and guided by the sleeve 15 will be held in such position that its axis will remain at all times in substantial alignment with the axis of the spindle.

The particular construction of the bearing 8 and the preferred method of forming the same will now be described more in detail.

- 10 A thin metal plate 17, which is roughly of triangular shape, is provided with a substantially central opening 18 and radial depressions 19 are formed therein extending from said opening. Depressions 21 are formed at the corners of the plate and lines 22 are scored upon the upper surface thereof. The corner portions are then bent upwardly, the bends occurring along the scored lines, to form a substantially pyramidal member provided with a central opening of suitable size for receiving the main spindle member 3. In this form the bearing member presents three upwardly tapering surfaces 23 and three upwardly tapering edges 24 which enter the bore in the bobbin and serve to support the bobbin centrally with respect to the main spindle member notwithstanding variations which may occur in the size of the bore in different bobbins whether 30 by reason of their having been formed originally with bores of different size or through wear. By means of this novel bearing member it is possible to use bobbins varying widely in the size of the internal bore as 35 well as bobbins in which the bore at one or both ends has become enlarged by excessive wear and insure the proper centering of the lower ends of the bobbins with their respective spindles. As previously stated when 40 the triangular bearing member is placed in operative position upon the main spindle member the radial depressions 19 formed in the base of the bearing member rest upon the upper face of the supporting member 5 to serve as reduced and rounded bearing surfaces for reducing the friction between the bearing and the supporting member and thus facilitating the readiness with which the bobbin will rotate relative to the spindle. 45 It will be seen that the upstanding annular flange 6 upon the supporting member gives the member a cup-shaped form which will permit the placing of a small supply of oil upon the upper surface of the supporting member where it will lubricate the contacting surfaces of the bearing and supporting members without danger of loss or escaping to come in contact with the thread or yarn. The provision of the novel bearing member 8 for centering the lower portion of the bobbin relative to the spindle in conjunction with the bearing sleeve 15 adjacent to the upper end of the main spindle member serves to maintain the bobbin in position so 50 that its axis is at all times in substantial

alignment with the axis of the spindle member and tilting of the bobbin thereby avoided while permitting the bobbin to rotate freely relative to the spindle member.

While I have shown and described the preferred embodiment of my invention with considerable particularity in order to make the construction and operation of the same clear to those skilled in the art, it is to be understood that I do not intend to be limited to the precise details of construction shown and described except as the same may be properly included within the scope of the appended claims when broadly construed in the light of my invention.

Having described my invention, what I claim is:

1. In a spindle structure for rotatably supporting a bobbin, the combination of a main spindle member, a member fixedly positioned relative to said main spindle member and having a portion extending upwardly of and circumferentially about a portion of said spindle member, and a pyramidal bearing member rotatably mounted upon said spindle member to center and rotatably support a bobbin relative to said spindle member.

2. In a spindle structure for rotatably supporting a bobbin, the combination of a main spindle member, and a pyramidal bearing member rotatably mounted upon said spindle member to center and rotatably support a bobbin relative to said spindle member.

3. In a spindle structure for rotatably supporting a bobbin, the combination of a main spindle member, a pyramidal bearing member for centering and rotatably supporting a bobbin upon said spindle member, and a guard member fixedly positioned relative to said spindle member for preventing yarn from becoming wound about said spindle member.

4. In a spindle structure for rotatably supporting a bobbin, the combination of a main spindle member, a pyramidal bearing member rotatably mounted upon said spindle member for centering and rotatably supporting a bobbin upon said spindle member, and a second bearing member carried by said spindle member above said first named bearing member and cooperating with said first named bearing member to maintain the longitudinal axis of the bobbin in substantial alignment with the longitudinal axis of the main spindle member.

5. In a spindle structure for rotatably supporting a bobbin, a main spindle member, a supporting member secured thereto, and a bearing member formed by bending a metal plate into the shape of a triangular pyramid, the base of which is a substantially equilateral triangle, and forming therein a central opening at substantially right angles

to the base thereof for the reception of said main spindle member whereby when the said bearing member is rotatably positioned upon the spindle member the apex of the pyramidal bearing will project within the bore of the bobbin and center the same relative to said main spindle member.

6. In a spindle structure for rotatably supporting a bobbin, a main spindle member, a supporting member secured thereto, and a bearing member rotatably mounted on said main spindle member and seated upon said

supporting member, said bearing being provided with a plurality of depressed radial ribs formed in the base thereof for contact with the face of said supporting member to render the said bearing readily rotatable on said supporting member and a tapered portion projecting within the bore of the bobbin.

In testimony whereof I have affixed my signature.

GEORGE W. DOVER.
